[57] CLAIM

The ornamental design for a cigar tip, as shown and described.

DESCRIPTION

FIG. 1 is a diagrammatic perspective view of the cigar tip in full lines with a cigar shown in broken lines representing environmental association matter being for illustrative purposes only and forming no part of the claimed invention; FIG. 2 is a right side elevational view thereof, the left side view being a mirror image of the right side view; FIG. 3 is a top plan view of the cigar tip, the bottom plan view being a mirror image of the top plan view; FIG. 4 is a rear elevational view thereof; and, FIG. 5 is a front elevational view thereof.
